UNITED STATES PATENT OFFICE.

JOHN B. BARTHOLOMEW, OF DES MOINES, IOWA.

PEANUT ROASTER AND WARMER.

SPECIFICATION forming part of Letters Patent No. 428,879, dated May 27, 1890.

Application filed November 5, 1888. Serial No. 289,952. (No model.)

To all whom it may concern:

Be it known that I, JOHN B. BARTHOLOMEW, a citizen of the United States of America, and a resident of Des Moines, in the county of 5 Polk and State of Iowa, have invented an Improved Peanut Roaster and Warmer, of which the following is a specification.

My object is to improve the appearance, convenience, and efficiency of a peanut-roaster; and my invention consists in the construction and combination of a spring and rotating cover with a driving-shaft and gearing to operate the roasting-cylinder, with a portable case, as hereinafter set forth, pointed 15 out in my claim, and illustrated in the accompanying drawings, in which—

Figure 1 is a side view of the complete machine, from which parts are broken away. Fig. 2 is an end view of the same, from which 20 parts are broken away. Fig. 3 is a side view of the gearing and an enlarged section of the case to which the frame that supports the gearing is attached. Fig. 4 is a perspective view of a heat-distributer adapted to be placed 25 under the roasting-cylinder and over the burners.

A represents a portable case of common form.

B is a driving-shaft in bearings formed in 30 or fixed to the opposite sides of the case.

C is a spring-cover at the end of the shaft B.

C² is a convolute spring fixed to the shaft at its inner end and to the inside of the outer portion of the cover C in such a manner that 35 power can be stored in the spring by rotating the cover.

d d are handles that project outward from the cover, so they can be seized by a person for the purpose of rotating the cover and 40 winding up the spring.

d' is a ratchet-wheel formed on or fixed to the periphery of the cover.

d'' is a pawl pivoted to the case A in such a manner that it will engage the ratchet-wheel and retain it stationary while the force 45 stored in the spring is gradually expended in rotating the driving-shaft B, as required to actuate the gearing connected with its opposite end and on the opposite side of the case A.

50 F represents a frame fixed to the side of the case to support gearing that will transmit power to the rotating roasting-cylinder G

from the driving-shaft, and also a governor to regulate the speed of the cylinder as required to roast nuts uniformly therein.

55

h are enlarged extensions on the ends of the journals of the cylinder for the purpose of facilitating the lifting and handling of the cylinder as required to fill in and empty nuts therefrom.

60

J is an open-topped tray, in which the nuts are placed after they are roasted. k is a water-reservoir fixed against its under side.

k' is a port or nozzle fixed in the bottom of the tray in such a manner that water can be 65 poured through it into the reservoir and then closed.

k'' is a steam-eduction tube connected with the reservoir.

m is a safety-valve connected with the tube 70 k''. m' is a steam-whistle connected with the same tube in such a manner that when the safety-valve is closed the whistle will serve as a safety-valve, and at the same time perform the function of a whistle to attract the 75 attention of persons as required to promote the sale of roasted nuts.

n is a tube fixed to the case in such a manner that it will extend inward under the roasting-cylinder to support hydrocarbon-burners 80 and upward at its opposite end to support an oil-reservoir n'.

n'' is a branch tube that extends from the tube n to support a burner under the reservoir k. It is provided with a stop-cock, so 85 that the burners under the roasting-cylinder may be operated without operating the burner under the water-reservoir at the same time.

r is a heat deflector and distributer made of perforated sheet metal and placed under 90 the cylinder G and over the burners under the cylinder in such a manner that it will aid in keeping a uniform heat in contact with the cylinder as required to roast the nuts evenly.

s is a door hinged to the end of the case in 95 such a manner that it can be turned down, as shown in Fig. 2, to gain access to the burners.

s' is a sheet-metal shield fixed to the inside of the wooden door to protect it from the heat generated by the burners under the rotating 100 cylinder.

To operate my improved peanut-roaster I store power in the spring C by rotating the cover C² and the ratchet-wheel combined

therewith. By means of the gearing and governor combined with the shaft of the motor and the cylinder and the spring-cover having a ratchet-wheel on its periphery the force of the spring is then applied to rotate the cylinder slowly at a uniform speed, while the heat generated by the burners roasts the nuts in the cylinder, and the steam generated in the water-reservoir will blow the steam whistle at the pleasure of the operator, and also heat the bottom of the tray and keep nuts warm that are placed in the tray after they are roasted.

I am aware that a water-reservoir and steam-chamber have been fixed to the bottom of the warming-pan of a nut-roaster, and that a steam-whistle has been combined with a nut-roaster; but my manner of combining a whistle and a safety-valve and a steam-generator with a nut-roaster is novel and advantageous in that the whistle is controlled by means of the safety-valve and the valve and whistle jointly connected with the generator by means of one tube.

I am also aware that spring-motors and governors have been combined with a rotat-

ing cylinder and hydrocarbon-burners located under the cylinder; but my manner of combining a spring and spring-cover and a rotating shaft and my arrangement and combination of a steam-generator, safety-valve and whistle, and hydrocarbon-burners with a portable case is novel and advantageous in that it produces a peanut-roaster that is improved in appearance, convenience, and efficiency.

30

35

I claim as my invention—

A rotating cylinder adapted to retain nuts, a driving-shaft connected with the cylinder by means of gearing, a convolute spring fixed to the driving-shaft, a rotating spring-cover placed loosely on the end of the driving-shaft and connected with the outer end of the spring, a continuous ratchet on the outer surface of the cover, and a pawl to engage the ratchet, arranged and combined with the frame and case of a peanut-roaster, to operate in the manner set forth, for the purposes stated.

JOIN B. BARTHOLOMEW.
